(57) **CLAIM**

The ornamental design for a food storage appliance, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-left perspective view of a food storage appliance according to a first embodiment of the claimed design;

FIG. 2 is a front perspective view thereof;

FIG. 3 is a front elevation view thereof;

FIG. 4 is a right side elevation view thereof;

FIG. 5 is a back elevation view thereof;

FIG. 6 is a left side elevation view thereof;

FIG. 7 is a top plan view thereof;

FIG. 8 is a bottom plan view thereof;

FIG. 9 is a front-left perspective view of a section of the food storage appliance taken along line 9-9 in FIG. 7;

FIG. 10 is a front-left perspective view of a section of the food storage appliance taken along line 10-10 in FIG. 7; and,

FIG. 11 is a front view of the section thereof.

A second embodiment of the claimed design is a mirror-image of the food storage appliance as depicted in FIGS. 1-11.

The portions of the article shown in broken line form no part of the claimed design.

Dash-dot lines adjacent un-shaded areas represent bounds of the claimed design and form no part of the claimed design themselves.

The portions of the article depicted in dark red have an appearance that includes a color described using the RGB definition: R/ 61 G/ 37 B/ 36.

The portions of the article depicted in dark grey have an appearance that has a color described as 90% black.
